DEVICE FOR APPLYING BACK PRESSURE TO
FORGINGS IN DRAWBENCH PASSESLe Roy Layton, Lansdowne, Pa., assignor to Lans-
downe Steel & Iron Company, Morton, Pa., a
corporation of Pennsylvania

Application June 4, 1942, Serial No. 445,798

14 Claims.

(Cl. 205—4)

This invention relates to a method and apparatus for improving the interior surfaces of the bottoms of the powder chambers of explosive-shell forgings.

The method and apparatus of the present invention are particularly adaptable for use in conjunction with the method and apparatus for finishing forgings disclosed in my prior U. S. Letters Patent No. 2,248,002, dated July 1, 1941, and No. 2,278,325, dated March 31, 1942. The present invention, however, is also applicable to other forms of the so called "draw benches" employed in the manufacture of hollow forgings of various kinds.

The external bottom surface of a shell forging occupies a plane at right angles to the coinciding longitudinal axes of the cylindrical body of the forging and the axial cavity which constitutes the powder chamber thereof; and the internal bottom of the powder chamber is usually 20 of a concentric parabolic or other tapering form.

The parabolic bottom of the powder chamber is usually formed over a mandrel which is forced into the primary piercing of the forging, whereby this piercing eventually constitutes the powder chamber.

By axial movement of the mandrel, the forging is advanced through single or multiple ring or roll passes having throats of progressively decreasing diameters respectively. The diameter 30 of each throat is, to some slight degree at least, smaller than the outside diameter of the forging, whereby the metal of the forging is radially condensed or compacted and stretched or formed over the paraboloidal nose and axially contiguous circular shank of the mandrel, which causes the internal parabolic surface of the bottom and the axially contiguous cylindrical bore of the powder chamber to conform to the external surfaces of said paraboloidal nose and correspondingly axial 40 contiguous circular shank of the mandrel, to shape and accurately dimension the interior of the powder chamber.

The piercing tool, which forms the primary piercing in the forging into which the mandrel is subsequently projected in normal course of usage, becomes pocked or grooved by abrasion, and when withdrawn from a piercing leaves small protuberances or ridges projecting from the internal surface of the piercing into the interior cavity thereof.

When the paraboloidal nose of the mandrel is inserted in the primary piercing, it engages the high spots of the protuberances and ridges, which prevents the entire area of the internal surface of the bottom of the powder chamber cavity from making complete over-all contact with the whole of the external surface of the nose of the mandrel.

If a ring pass is employed in the finishing

process and the diameter of the throat thereof is sufficiently smaller than the outside diameter of the forging to apply enough resistance to the advancing of the forging through said throat by 5 said mandrel to flatten out the aforesaid protuberances, ridges, etc., the external bottom surface of the forging is frequently bulged from its normal flat planar condition and in some instances is actually perforated by the nose of the mandrel, under the force required to advance the forging through the throat of the ring die.

If a roll pass is employed for finishing the forging, the possibilities of the bulging or perforating of the exterior bottom of the forging are practically eliminated, however, the protuberances remain within the powder chamber and prevent proper contact of the inner surface thereof with the nose of the mandrel.

If the throat of the roll pass is excessively decreased to apply sufficient resistance to the forward motion of the forging to effect flattening of the protuberances by the nose of the mandrel, the parabolic bottom of the powder chamber is frequently squeezed away from and elongated in front of the paraboloidal nose of the mandrel, as the portion of the forging lying in the cross sectional plane of or adjacent the extremity of the nose passes through the bite of the rolls of said pass, leaving a space between the nose of the mandrel and the bottom surface of the powder chamber which distorts said chamber.

The principal object of the present invention is to eliminate each and all of the aforesaid disadvantages of the finishing processes now being employed.

Another object of the invention is to flatten out all of the objectionable protuberances, ridges, etc., on the interior surfaces of the powder chambers of the forgings, without bulging or perforating the shell bottoms.

Another object of the invention is to provide a flat faced anvil against which the exterior bottom surface of the shell forgings bear as said forgings are forced through the throats of the ring or roll passes during the finishing of the interior surfaces of their powder chambers, whereby axial bulging or perforating of the shell bottoms are prevented.

Another object of the invention is to provide 50 means for applying a predetermined back pressure or resistance against the normally flat external bottom surface of a forging, through the aforesaid anvil, to the advancing movement of the shell forging through the ring or roll pass, in opposition to the power applied to the mandrel for effecting said advancing of the shell forging.

Another object of the invention is to provide 55 means for controlling the back pressure applied by the anvil, and for releasing said back pressure immediately after the paraboloidal end of

the mandrel has advanced through the ring or roll pass.

Another object of the invention is to provide means for projecting the back pressure anvil through the throat of a secondary ring or roll pass to the plane of initial contact of the bottom end of the shell forging with the rolls or ring forming the throat of an initial ring or roll pass.

The construction and operation of the mechanism of the present invention, in conjunction with the finishing mechanism disclosed in the aforesaid prior U. S. Letters Patent, will be fully disclosed hereinafter, reference being had to the accompanying drawings, of which:

Fig. 1 is a side elevation of the apparatus of the present invention coupled, in tandem, to the apparatus of the aforesaid Letters Patent;

Fig. 2 is an enlarged longitudinal vertical sectional elevation disclosing the back pressure mechanism in its resistance-affording position;

Fig. 3 is a view corresponding to Fig. 2 but showing the resistance-affording mechanism in its effective position;

Fig. 4 is a transverse sectional elevation taken on the line 4-4, Fig. 1;

Fig. 5 is a transverse sectional elevation taken on the line 5-5, Fig. 1;

Fig. 6 is a transverse sectional elevation taken on the line 6-6, Fig. 1;

Fig. 7 is a transverse sectional elevation taken on the line 7-7, Fig. 1;

Fig. 8 is a transverse sectional elevation taken on the line 8-8, Fig. 1;

Fig. 9 is a sectional plan view taken on the line 9-9, Fig. 1;

Fig. 10 is an end view as seen from the plane and direction indicated by the arrow-bearing line 10-10, Fig. 1;

Fig. 11 is a longitudinal sectional elevation of a shell forging showing protuberances in the powder chamber left by a pocked and scored primary piercing tool; and

Fig. 12 is a view similar to Fig. 11, but showing the irregularities in the wall of the powder chamber after being eradicated by use of the method and apparatus of the present invention.

As disclosed in the two aforementioned prior patents, and as shown in Fig. 1 of the present case, a hot primary forging B², which has been pierced to form the powder chamber thereof, is placed in a horizontally disposed trough 9, with the longitudinal axis of the forging coaxially aligned with the longitudinal axis of the finishing tool or mandrel 10.

The pre-formed piercing C² is slightly greater, cross-sectionally, than the mandrel 10, at substantially all corresponding cross-sectional planes of the mandrel and the forging.

The mandrel 10 is advanced axially into the cavity C² of the primary forming B², freely and without making any substantial contact with the interior walls of the cavity, until the extreme outer end 11 of the mandrel comes into contact with the extreme inner bottom end c² of the cavity C². Continued axial movement of the mandrel 10 advances the forging B² into the bite of a series of rolls R¹, R¹ having concave peripheral faces which collectively constitute the throat of a first or preliminary pass, concentric to the longitudinal axis of the horizontally movable mandrel 10.

Continued axial movement of the mandrel 10 in the direction of the arrow a¹, Fig. 1, forces the forging B² through the first roll pass, formed by the rolls R¹, R¹, into and through the bite of a

series of rolls R², R² which collectively constitute the throat of a second or finishing roll pass, concentric to the axis of the mandrel 10.

The throat of the first roll pass is of slightly smaller diameter than the outside diameter of the forging B², consequently, as the forging is advanced through the first roll pass, its outside diameter is reduced to that of the pass, which effects a radial contraction and compacting of the metal of the forging around the outer surface of the mandrel 10, bringing the interior surface of the powder chamber or cavity C² into close intimate contact with the outer surface of the mandrel.

The diameter of the second roll pass is very slightly smaller than the diameter of the forging after it leaves the first roll pass and acts, primarily, to reduce any fine ridges that may have been formed on the outer surface of the forging by the abutting edges of the rolls of the first pass, it being noted that, as disclosed in the prior patents, the rolls of the second pass are staggered to the extent of 90 degrees about the axis of the mandrel with respect to the rolls of the first pass.

The external normally flat bottom b² of the forging B² is formed in a plane x-x at right angles to the longitudinal axis y-y of the forging. The bottom b² is provided with a pad b which extends outwardly beyond the plane x-x of the bottom b² and is of a smaller diameter than said bottom.

According to the present invention, when the bottom plane x-x of the forging B² advances, in the direction of the arrow a¹, Fig. 1, to the plane X-X of the bite of the rolls R¹, R¹ of the first pass, said forging bottom b² is engaged by a transverse flat face 12 of an anvil 15 which has been conversely advanced in the direction of the arrow a² through the rolls R², R² of the second pass until the plane of the face 12 of the anvil coincides with the plane X-X of the bite of the rolls R¹, R¹ of the first pass.

The end face 12 of the anvil 15 is provided with a recess 13 into which the axial projection b of the forging B² extends.

The mandrel 10 is advanced in the direction of the arrow a¹, under a predetermined hydraulic force of, for example, 90 tons per square inch pressure, which is opposed in the direction of the arrow a² by a back pressure of, for example, 40 tons per square inch pressure, applied to the anvil 15. Consequently, as the nose of the mandrel 10 moves into the cavity C² of the forging B² and engages the high spots of any protuberances, ridges or other irregularities C³ (Fig. 11) on the inner parabolic bottom surface of the cavity C², continued advance of the mandrel 10 in the direction of the arrow a¹ freely advances the forging into the bite of the rolls R¹, R¹. Further advance of the forging B² by the mandrel 10 is then opposed by the mandrel 15.

The opposing force applied by the anvil 15 and distributed uniformly over the entire area of the external bottom surface b², momentarily stops the forging B² while the mandrel 10 continues to advance. Thus, any protuberances, ridges, or other irregularities encountered in the bottom c² of the cavity C² are flattened out by the paraboloidal end 11 of the mandrel 10.

After flattening of any protuberances etc. encountered in the base c² of the cavity C², the pressure exerted in the direction of the arrow a¹ by the mandrel 10 overcomes the pressure exerted in the direction of the arrow a² by the anvil 15, and the anvil 15 is caused to recede as a

result of the greater advancing force supplied to the forging B^2 by the mandrel 10 while the opposing pressure exerted by the anvil is continued until the tapering or paraboloidal end of the mandrel 10 , and the correspondingly shaped cavity C^2 of the forging B^2 , from the end b^2 to the cross-sectional plane $z-z$ thereof have passed through the bite of the rolls R^1, R^1 , whereupon, the back pressure applied by the anvil 15 is released and no further resistance to the normal advance of the forging B^2 through the rolls R^1, R^1 and R^2, R^2 by the mandrel 10 is presented.

The forging B^2 is advanced by the mandrel 10 until the rear or open end b^1 of the forging has passed through and beyond the housing 16 in which the rolls R^2, R^2 are rotatably mounted, and beyond a stripper plate 18 which is slidably mounted in guides $17, 17$ on the rear end of the housing 16 . After the forging B^2 has passed completely beyond the stripper plate 18 , said stripper plate is moved transversely into the path traversed by the forging, to form an abutment for the end b^1 of the forging, after which, reversal of the direction of the movement of the mandrel 10 causes the rear end b^1 of the forging B^2 to engage the stripper plate 18 , thereby forcing the forging off the mandrel 10 as said mandrel returns to its normal position beyond the front end trough 9 , for the beginning of another cycle.

In the present instance, the anvil 15 is removably mounted on one end of a horizontally operable ram 20 . The anvil 15 is provided with a threaded axial extension $15a$ which is screwed into a threaded cavity formed in one end of the ram 20 .

The ram also includes a rearwardly extending cylindrical end 21 , of a diameter suitable for passage through the throat formed by the rolls R^2, R^2 , and a rectangular cross-head section 22 which is slidably mounted in a lower guideway $23a$ and an upper guideway $23b$.

The cylindrical section 21 of the ram 20 is interchangeably mounted on one end of the cross-head 22 by an axial threaded projection $21a$ screwed into a correspondingly threaded bore in the cross-head 22 .

The rear end section 24 of the ram 20 , like the anvil 15 is removably connected to said ram by an axial threaded projection $24a$ screwed into a correspondingly threaded bore in the rectangular cross-head 22 of the ram 20 .

The forward end face 19 of the ram 20 is adapted to be engaged by a roller 25 , which is rotatably mounted in a forked end of one arm of a triangular or bell crank lever 26 . The bell crank lever 26 is pivotally mounted on a shaft 27 , between a pair of laterally spaced uprights $28, 28$. The second arm of the bell crank lever 26 is forged and provided with a roller 29 which is engaged by the lower end of a vertically moving plunger 30 . The plunger 30 is slidably mounted in a vertical cylinder 31 having a base 32 which is secured to the upper ends of the uprights $28, 28$, as by bolts 33 .

Fluid pressure is admitted to the upper end of the cylinder 31 through a pipe 34 , from a source capable of producing a force of 40 tons per square inch against the rear end 19 of the ram 20 , through the bell crank lever 26 .

Axially aligned with, and superposed on, the cylinder 31 is a return cylinder 35 , in which is slidably mounted a vertically movable plunger 36 . The upper end of the plunger 36 is provided with a cross-head 37 which is rigidly con-

nected to a cross-head 38 on the lower end of the plunger 30 by a pair of tie rods $39, 39$.

The cylinder 35 is connected to a constant source of uniform pneumatic pressure, by a conduit 40 , which at all times admits fluid under pressure to the lower end of the plunger 36 , within cylinder 35 , and opposes the downward movement of the plunger 30 by fluid pressure admitted to the cylinder 31 through the conduit 34 .

As soon as the mandrel 10 has moved the forging B^2 through the throat of the roll pass formed by the rolls R^1, R^1 , and when the transverse plane $z-z$ of the forging substantially coincides with the plane $X-X$ of the bite of the rolls R^1, R^1 , the fluid supply to the cylinder 31 through the conduit 34 is manually or automatically cut off and permitted to exhaust by the reverse movement through the conduit 34 , whereupon, the constant uniform pressure entering the lower end of the cylinder 35 through the conduit 40 returns the plunger 30 to its upper or normal inactive position shown in Fig. 3.

Further advancing movement of the forging B^2 by the mandrel 10 slides the ram 20 in its guideways $23a-23b$ until the rear end 19 of said ram engages a resilient buffer 41 , which brakes the accelerated forward movement of the forging B^2 which takes place when the rear end b^1 of the forging B^2 leaves the bite of the rolls R^2, R^2 .

The buffer head 41 is provided with a stem 42 which is slidably mounted in a cross member 43 located at the rear end of the guideway $23a-23b$ for the ram 20 . The rear end of said stem 42 is slidably mounted in a buffer plate 44 . The stem 42 of the buffer 41 is provided with an adjustable flanged nut 45 between which and the buffer plate 44 is mounted the buffer spring 46 .

The anvil 15 is projected through the throat of the pass formed by the rolls R^2, R^2 , and into the throat of the pass formed by the rolls R^1, R^1 , in the present instance, by one or the other of a pair of dogs $47, 47$ which are carried by an endless chain 48 . The rear face 19 of the ram 20 is provided with a recess 49 into which one of the dogs 47 enters and slides the ram 20 and anvil 15 along the guideway $23a-23b$, in the direction of the arrow a^2 , until the roller 25 on the bell crank lever 26 , which, during said sliding of the ram 20 travels along the top of the ram 20 , rides down and against the rear end 19 of the ram.

The chain 48 at the uprights $28, 28$, is seated in a circumferential groove 50 formed in the face of a roller 51 , which is rotatably mounted, between said uprights, on a shaft 52 having its opposite ends journaled in a bearing formed in or carried by a pair of brackets $56, 56$ secured to the uprights $28, 28$.

Between the grooved wheel 51 and the rear end of the guideway $23a-23b$ for the ram 20 , the chain 48 rides in a circumferential groove 53 formed in a second wheel 54 which is rotatably mounted on a shaft 55 having its opposite ends journaled in or carried by said pair of brackets $56, 56$ which are secured to the uprights $28, 28$.

The outer peripheral surfaces of the grooved wheels 51 and 54 serve to support the rear end of the cross-head 22 which is projected beyond the rear end of the cross-head guide $23a$ when the cylindrical end 21 and anvil 15 of the ram 20 are projected into and through the throat formed by the rolls R^2, R^2 .

The uprights $28, 28$ are spaced from and rigidly secured to the frame 16 , which houses the pass rolls R^2, R^2 , by a pair of upper laterally spaced

stringers 57, 57, and by a lower stringer bolt 58. The rear end of the bolt 58 is anchored in a spacing member 59 supported by and between the uprights 28, 28 and to which said spacing member is secured by a series of bolts or rivets 60, 60. The over-hanging end of the base 32 of the cylinder 31 is supported by means of angular braces 61, 61 which are secured at their one end to the uprights 28 by bolts 62, 62, and at their opposite end to the base 32 by bolts or rivets 63, 63.

The buffer block 43 is supported by a pair of laterally spaced uprights 64, 64. The uprights 64, 64 are secured to and spaced from the uprights 28, 28 by a pair of upper horizontally extending tie bolts 66 and a pair of lower horizontally extending tie bolts 67, 67. The buffer plate plate 44 is secured to the rear sides of the uprights 64 by the tie rods 66, 66 and 67, 67.

The upper guideway 23b, for the ram 20, is provided with transversely extending arms 68, 68 which are mounted on the tie bolts 66, 66 and the lower guideway 23a is provided with a pair of transversely extending arms 69, 69 which are supported by the lower tie bolts 67, 67. The lower guideway 23a is provided with a longitudinal groove 76, in which the chain 48 travels beneath the ram 20.

The end of the chain 48 adjacent the uprights 64, 64, passes around a sprocket 70 which is secured to a transverse shaft 71, intermediate a pair of brackets 72, 72, which are respectively secured to the uprights 64, 64 by bolts 73, 73. The shaft 71 is rotatably mounted in the brackets 72 and is provided with a hand wheel 75, by which the chain 48 may be operated to move the ram 20 and anvil 15 in the direction of the arrow a², and into position to back up a forging advanced into the bite of the rolls R¹, R¹ by the mandrel 10.

As shown in Fig. 4, the bell crank lever 26 is formed of three rigidly connected parts including a pair of outside members 26a, 26a, and an intermediate member 26b, with all three parts rigidly secured together by rivets etc. The intermediate member 26b is provided with recesses 77 and 78 in which the rollers 25 and 29, respectively, rotate.

The lower end of the plunger 30 is provided with an interchangeable insert 79 against which the roller 29 of the bell crank lever 26 rides, for replacement in case of excessive wear resulting from the heavy pressure transmitted thereby.

The cylindrical section 21 and anvil 15 are interchangeably mounted in the ram 20 for changing in accordance with changes in the diameters of the forging being worked by the apparatus and corresponding variations in the diameters of the throats of the passes R¹, R¹ and R², R².

While the shape of the bottom of the cavity C² has herein been described as being parabolic and the shape of the nose of the mandrel 10 has herein been described as being paraboloidal, it will be understood that the bottom of the cavity and the nose of the mandrel may be of a frustoconical or tapering shape without departing from the spirit of the invention and without interfering with or requiring changes in the mode of operation of the apparatus or the principles of the method.

Obviously the details of the structure may be varied according to the whims of the individual machine designers without affecting the principles of the invention.

It will be understood that the cavity C², while referred to as a "powder" chamber is adapted

to receive any of the well known explosives commonly employed in high explosive shells.

I claim:

1. A forging apparatus, comprising a pass, a mandrel engageable with the interior bottom surface of a hollow forging to force the forging completely through said pass, means engageable with the exterior bottom surface of the forging for resiliently opposing initial axial movement of the forging through said pass by said mandrel, and means for rendering said opposing means ineffective after said mandrel has advanced said forging a distance less than the full length of the forging through said pass.

2. A forging apparatus, comprising a pass, a mandrel engageable with the interior bottom surface of a hollow forging to force the forging completely through said pass, means including an anvil engageable with the exterior bottom surface of the forging for resiliently opposing initial axial movement of the forging through said pass by said mandrel, and means for rendering said opposing means ineffective after said mandrel has advanced said forging a distance less than the full length of the forging through said pass.

3. A forging apparatus, comprising a pass, a mandrel engageable with the interior bottom surface of a hollow forging to force the forging completely through said pass, an anvil engageable with the exterior bottom surface of the forging, means for applying a predetermined force to said anvil for resiliently opposing initial axial movement of the forging through said pass by said mandrel, and means for rendering said opposing means ineffective after said mandrel has advanced said forging a distance less than the full length of the forging through said pass.

4. A forging apparatus, comprising a pass, a mandrel engageable with the interior bottom surface of a hollow forging to force the forging completely through said pass, an anvil engageable with the exterior bottom surface of the forging, a ram axially aligned with said mandrel and supporting said anvil, means for applying a predetermined force to said ram for resiliently opposing initial axial movement of the forging through said pass by said mandrel, and means for rendering said opposing means ineffective after said mandrel has advanced said forging a distance less than the full length of the forging through said pass.

5. A forging apparatus, comprising a pass, a mandrel engageable with the interior bottom surface of a hollow forging to force the forging completely through said pass, an anvil engageable with the exterior bottom surface of the forging, a ram axially aligned with said mandrel and supporting said anvil, means for applying a predetermined force to said ram including a plunger operable in one direction in a cylinder under fluid pressure for resiliently opposing initial axial movement of the forging through said pass by said mandrel, and means for rendering said opposing means ineffective after said mandrel has advanced said forging a distance less than the full length of the forging through said pass.

6. A forging apparatus, comprising a pass, a mandrel engageable with the interior bottom surface of a hollow forging to force the forging completely through said pass, an anvil engageable with the exterior bottom surface of the forging, a ram axially aligned with said mandrel and supporting said anvil, means for applying a predetermined force to said ram including a plunger disposed at an angle to the axis of said ram and

operable in one direction in a cylinder under fluid pressure, and a bell crank lever operable between said plunger and said ram for resiliently opposing initial axial movement of the forging through said pass by said mandrel.

7. A forging apparatus, comprising a pass, a mandrel engageable with the interior bottom surface of a hollow forging to force the forging completely through said pass, an anvil engageable with the exterior bottom surface of the forging, a ram axially aligned with said mandrel and supporting said anvil, means for applying a predetermined force to said ram including a plunger operable in one direction in a cylinder under fluid pressure for resiliently opposing initial axial movement of the forging through said pass by said mandrel, and means for rendering said opposing means ineffective after said mandrel has advanced said forging a distance less than the full length of the forging through said pass, and means constantly opposing said movement of said plunger in said one direction resiliently for moving said plunger reversely upon discontinuance of said fluid pressure to said cylinder.

8. A forging apparatus, comprising a pass, a mandrel engageable with the interior bottom surface of a hollow forging to force the forging completely through said pass, an anvil engageable with the exterior bottom surface of the forging, a ram axially aligned with said mandrel and supporting said anvil, means for moving said ram in one direction to apply a predetermined force to said ram for resiliently opposing initial axial movement of the forging through said pass by said mandrel, and means for rendering said opposing means ineffective after said mandrel has advanced said forging a distance less than the full length of the forging through said pass, and a buffer engageable by said ram to check movement thereof in the opposite direction when said force is released.

9. A forging apparatus, comprising a pass, a mandrel engageable with the interior bottom surface of a hollow forging to force the forging through said pass, an anvil engageable with the exterior bottom surface of the forging, a ram axially aligned with said mandrel and supporting said anvil, means including a bell crank lever pivoted adjacent the path of movement of said ram and having one arm engageable with a transversely extending face of said ram for applying a predetermined force to said ram for resiliently opposing initial axial movement of the forging through said pass by said mandrel, said arm being movable out of the path of said ram upon predetermined partial movement of said forging through said pass by said mandrel and means for moving said ram into position for engagement by said bell crank and said forging prior to the application of said force to said ram.

10. A forging apparatus, comprising a pass, a guideway beyond one end of said pass, a mandrel engageable with the interior bottom surface of a hollow forging to force the forging completely through said pass, a ram axially aligned with said mandrel and engageable with the exterior bottom surface of the forging for resiliently opposing initial axial movement of the forging through said pass by said mandrel, said ram including a cross-head slidably mounted in said guideway, and a cylindrical portion movable into said pass to engage said exterior end of said forging.

11. A forging apparatus, comprising a pass, a horizontal guideway beyond one end of said pass, a horizontal mandrel engageable with the interior bottom surface of a hollow forging to force the forging completely through said pass, a ram slidably mounted in said guideway in axial alignment with said mandrel and engageable with the exterior bottom surface of the forging, a vertically movable plunger operable in one direction in a vertically disposed cylinder under fluid pressure, and a bell crank lever having one arm engageable by said plunger and a second arm engageable with said ram for resiliently opposing initial axial movement of the forging through said pass by said mandrel.

12. A forging apparatus, comprising a horizontal pass, a horizontal guideway, a horizontally movable mandrel engageable with the interior bottom surface of a hollow forging to force the forging completely through said pass, a horizontally movable ram slidably mounted in said guideway in axial alignment with said mandrel and engageable with the exterior bottom surface of the forging, and means for applying a predetermined force to said ram including a vertically operable plunger operable in one direction in a vertically disposed cylinder under fluid pressure, and a bell crank lever having one arm engageable by said plunger and a second arm engageable with said ram for resiliently opposing initial axial movement of the forging through said pass by said mandrel.

13. A forging apparatus, comprising a horizontal pass, a horizontal guideway, a horizontally movable mandrel engageable with the interior bottom surface of a hollow forging to force the forging completely through said pass, a horizontally movable ram slidably mounted in said guideway in axial alignment with said mandrel and engageable with the exterior bottom surface of the forging, and means for applying a predetermined force to said ram including a vertically operable plunger operable in one direction in a vertically disposed cylinder under fluid pressure, and a bell crank lever having one arm engageable by said plunger and a second arm engageable with said ram for resiliently opposing initial axial movement of the forging through said pass by said mandrel.

14. The method which comprises inserting a shaping mandrel in a cavity of a hollow forging for engagement with the interior bottom surface of the hollow forging, applying a predetermined force to said mandrel for pushing said forging in one axial direction through the throat of a reducing pass, and applying a lesser counter-directional force to the exterior bottom surface of said forging for resiliently opposing initial axial movement of the forging through said pass by said mandrel to insure full surface engagement between said mandrel and the surrounding wall of said cavity and discontinuing said counter-directional force after a predetermined partial movement of the forging through said pass has been effected.

15. The method which comprises inserting a shaping mandrel in a cavity of a hollow forging for engagement with the interior bottom surface of the hollow forging, applying a predetermined force to said mandrel for pushing said forging in one axial direction through the throat of a reducing pass, and applying a lesser counter-directional force to the exterior bottom surface of said forging for resiliently opposing initial axial movement of the forging through said pass by said mandrel to insure full surface engagement between said mandrel and the surrounding wall of said cavity and discontinuing said counter-directional force after a predetermined partial movement of the forging through said pass has been effected.

LE ROY LAYTON.
